UNITED STATES PATENT OFFICE.

VALENTINE SCHUCK, OF NEW YORK, N. Y., ASSIGNOR TO THE SUTRO BROTHERS BRAID COMPANY, OF NEW YORK.

DESIGN FOR BRAID.

SPECIFICATION forming part of Design No. 18,641, dated September 25, 1888.

Application filed August 10, 1888. Serial No. 282,468. Term of patent 14 years.

To all whom it may concern:

Be it known that I, VALENTINE SCHUCK, of the city, county, and State of New York, have invented a new and original Design for Braid for Trimming Ladies' Garments and for other Purposes; and I do hereby declare that the following is a full and exact description thereof, reference being had to the accompanying drawings, and to the letters of reference marked thereon, making a part of this specification, in which—

Figure 1 is a plan view of a piece of braid showing my new design; and Fig. 2 is an edge view of the same, illustrating the design more fully.

The leading feature of my design is a systematic series of helicoidal figures appearing in bas-relief along one edge of a flat piece of braid and producing the effect to the eye of a piece of cord woven spirally into said edge.

A in the drawings represents a piece of flat braid, having one of its edges, D, perfectly plain and straight in outline. The parallelism therewith of its opposite edge, c, is interrupted at regular intervals by helicoidal figures D D D appearing thereon in bas-relief, and which extend inwardly from the edge, as shown in the drawings. By reason of the projection of the curved ends of these helicoidal figures D D D beyond a line drawn parallel with the opposite straight edge, B, of the braid, the edge,

c, bordered by said figures represents an irregular outline consisting of a series of straight lines, e e e, and intervening convex curves, f f, (see Fig. 1,) while the otherwise flat surface of the braid along said edge, on either side thereof, is relieved by the series of curved elevations defined in outline by said figures D D D, and extending severally inward on both faces thereof from the convex curves f f, defining its margin, and consequently presents likewise an irregular outline consisting of alternate straight lines m m and convex curves n n, as shown in Fig. 2.

What I claim is—

The design for braid herein shown and described, the same comprising a straight longitudinal margin on one side of the piece of braid and a series of helicoidal figures appearing in bold relief along its opposite parallel edge and interrupting the straight outline of said edge and of both marginal faces thereof, whereby a series of straight lines alternating with convex curves are presented along said edge and marginal faces.

In testimony whereof I have signed my name to this specification in the presence of two subscribing witnesses.

VALENTINE SCHUCK.
